UNITED STATES PATENT OFFICE

135,986

DESIGN FOR AN APPLIQUÉ OR THE LIKE

Virgil F. Hubert, Coronado, Calif., assignor to Consolidated Vultee Aircraft Corporation, San Diego, Calif., a corporation of Delaware

Application May 5, 1943, Serial No. 110,127

Term of patent 7 years

To all whom it may concern:

Be it known that I, Virgil F. Hubert, a citizen of the United States, residing at Coronado, in the county of San Diego and State of California, have invented a new, original, and ornamental Design for an Appliqué or the like, of which the following is a specification, reference being had to the accompanying drawing forming a part thereof.

In the drawing:

Figure 1 is a front view of an appliqué or the like, showing my new design; and Figure 2 is an edge view.

I claim:

The ornamental design for an appliqué or the like, substantially as shown.

VIRGIL F. HUBERT.
